UNITED STATES PATENT OFFICE

159,246

PENCIL FERRULE

Harry U. Bittman, East Orange, N. J.

Application April 5, 1950, Serial No. 8,997

Term of patent 14 years

(Cl. D74—1)

To all whom it may concern:

Be it known that I, Harry U. Bittman, a citizen of the United States of America, residing at East Orange, in the county of Essex and State of New Jersey, have invented a new, original, and ornamental Design for a Pencil Ferrule, of which the following is a specification, reference being had to the accompanying drawing forming a part thereof.

The figure is a perspective view of a pencil ferrule, showing my new design.

I claim:

The ornamental design for a pencil ferrule, substantially as shown.

HARRY U. BITTMAN.
